MEANS AND METHOD FOR REGULATING
THE FLUID CONTENT OF CAPILLARY IN-
STRUMENTSHugo Engelhardt, Philadelphia, Pa., assignor to
Precision Thermometer and Instrument Co.,
Philadelphia, Pa., a corporation of Pennsylvania

Application October 17, 1932, Serial No. 638,187

5 Claims. (Cl. 200—141)

My invention is designed to provide improved means and method for regulating the fluid content of the bore and bulb of a temperature sensitive instrument so that such instrument may be 5 readily adjusted or set with greater accuracy.

In accordance with my invention the fluid content of the bore is adjusted by contracting the contents of the bulb forming a supply reservoir for the bore and thereby creating a vacuum in the 10 bore while the instrument is disposed in an upright position with the top of the bore sealed by an auxiliary pool of similar fluid positioned above the bore and from which fluid is drawn into the bore by the conjoint action of the vacuum in the 15 bore and the weight or gravity acting on the superimposed sealing pool.

The communication between the chamber containing the sealing pool and the bore is preferably so constricted as to prevent the initiation of 20 downward flow into the bore unless the action of the vacuum therein is augmented by the weight of a substantial body of fluid in such chamber above the bore. Hence by displacing all or the bulk of the sealing pool from its chamber above the bore, 25 the instrument may be cooled without causing flow of additional fluid into the bore, or the whole or the bulk of the sealing pool may be held in the sealing chamber above the bore without initiating flow into the bore until the instrument is cooled.

30 When the bore has been filled by the joint action of suction and gravity to a level above the content desired and preferably to its top, the auxiliary pool is displaced from its sealing position in the chamber above the bore. The excess 35 fluid contained in the bore is then expelled from the upper end of the bore by expanding the contents of the bulb and bore to such extent that when the fluid content is contracted to a desired degree it will have a level or volume desired under 40 given temperature conditions. The expelled liquid is insufficient in weight to force it past the constriction back into the bore when the shrinkage of fluid therein by cooling again creates a vacuum, and such expelled fluid may be disposed 45 from the top of the bore and added to the auxiliary pool for future use.

My improvements are particularly applicable 50 to thermostatic devices controlling circuits for regulating and maintaining temperatures of crystals used in the transmission of radio waves where a very slight variation in the temperature of the crystal results in a substantial variation in the wave lengths transmitted.

55 In the application of my improvements to such devices, conducting wires, preferably of platinum

connected in a circuit, may be embedded in a 5 glass tube so as to pierce the wall of a capillary bore extending longitudinally through a portion of the tube and communicating at its lower end with a bulb forming a main reservoir for a conducting liquid sensitive to temperature changes, as, for instance, mercury. The hollow upper end 10 of the tube is of substantially greater caliber than the capillary bore and may have a portion thereof bent over to leave a sealing chamber immediately 15 above the capillary bore and form a chamber beside the sealing chamber and providing an auxiliary reservoir into which a pool of fluid may be readily shifted from the sealing chamber or vice versa.

15 Communication between the sealing chamber and the bore is controlled by a glass rod anchored to the wall of the sealing chamber and having its depending end projecting into the top of the bore so as to constrict the passage therethrough sufficiently to interrupt and prevent continuous flow 20 of a thermostatic liquid unless such thermostatic liquid has a substantial head and is subjected to an unbalanced pressure in addition to its weight.

The characteristic features and advantages of 25 my improvements will further appear from the following description and the accompanying illustration of a preferred embodiment thereof.

In the drawing, Fig. 1 is an elevation of a thermostatic device embodying my improvements; 30 Fig. 2 is a longitudinal sectional view thereof, and Fig. 3 is an enlarged longitudinal sectional view of the upper end of the instrument shown in Figs. 1 and 2 showing globules of mercury passing 35 down the constricted section of the bore.

In the illustrative embodiment of my invention illustrated in the drawing, a glass rod 1 has at the bottom thereof a bulb 2 communicating at its top with a capillary bore 3 having a contraction chamber 4 intermediate the ends thereof to avoid 40 separation of the mercury column in the capillary bore should the instrument be suddenly subjected to excessive cold. The hollow upper end 5 of the glass rod has a caliber similar to that of the bulb 2 and provides a spillway or sealing chamber 6 45 and is bent to substantially V-shape to form an auxiliary reservoir 7 in the depending leg. A glass rod 8 is fused to the inner wall of the chamber 6 and has a depending end 9 disposed within and almost closing the top of the bore 3. A pair 50 of platinum wires 10 and 11 are sealed in the wall of the tube 1 with their inner ends piercing the wall of the capillary bore at spaced points above the contraction chamber 4. The instrument contains sufficient mercury 12 to fill the 55

bulb 2, the contraction chamber 4 and the bore section between them under minimum temperature conditions, and in addition thereto an auxiliary pool of mercury 12' is provided which may be thrown, by flicking the instrument, into the chamber 6 or into the chamber 7. The quantity of mercury 12' is insufficient to flow of its own accord from the chamber 7 into the chamber 6 in the upright position of the instrument and the chamber 6 is too small to contain sufficient mercury for its head alone to initiate flow past the rod 8 into the bore 3. The wire 11 enters the bore 3 a distance below the top of the bore equal to the movement of the meniscus of the mercury column as a result of a pre-determined temperature change, say, one degree. Each of the wires 10 and 11 is connected with a conducting ring 13 and 14 which have connected therewith conductors 15 and 16 of a circuit containing temperature regulating instrumentalities, such as heating coils, not shown.

When it is desired to set the instrument so that it will operate to close the circuit containing the wires 15 and 16 at a temperature below that for which the instrument was previously set, it is necessary to increase the mercury content of the bore 3 from the auxiliary pool 12'. To effect this, the auxiliary pool 12' is shifted from the chamber 7 (Fig. 2) into the chamber 6 (Fig. 3) and while the instrument is in upright position the bulb 2 is subjected to a temperature substantially below that at which it is desired that the instrument operate to close the circuit. The cooling and contraction of the mercury in the bulb causes the mercury column to fall and create a vacuum between the meniscus of the column and the bottom of the pool 12' sealing the top of the bore. The suction thus created augments the head of the pool 12' to start flow therefrom past the rod 8 into the bore, which may be continued until the bore is filled. The remainder of the mercury 12' is then shifted into the chamber 7 and the bulb 2 is immersed in a bath or oven having a temperature sufficiently higher than the temperature at which it is desired that the instrument close the circuit to cause a movement of the meniscus of the mercury column a distance equal to the distance between the wire 11 and the top of the bore. If, for instance, the distance between the wire 11 and the top of the bore is equal to the distance moved by the meniscus of the mercury column upon a change of one degree in temperature, and it is desired that the instrument operate to close the circuit at say, fifty degrees, the bulb should be inserted in a bath or oven having a temperature of fifty-one degrees. This will expel from the bore, past the rod 8, all the mercury in excess of that required to bring the meniscus of the column into contact with the wire 11 at fifty degrees. The mercury thus expelled into the spill chamber 6 has too little volume and head to flow back past the rod 8 into the bore when the bulb is removed from the bath or oven, and may be thrown over into the chamber 7.

When it is desired to set the instrument to operate to close the circuit at a temperature above that for which it was previously set, it is of course, unnecessary to draw any mercury into the bore from the auxiliary pool, and the instrument is accurately set while in an upright position by merely inserting its bulb into a bath or oven having a temperature one degree above that at which it is desired the instrument operate, so as to expel from the bore past the rod and into

the spill chamber 6 the mercury in excess of that required to bring the meniscus of the mercury column into contact with the wire 11 at the temperature at which it is desired the instrument operate.

5

By my improvements, I have provided an instrument which will operate within much less than the tolerance of one-tenth of a degree permissible in controlling the temperature of radio crystals, and which may be quickly, simply and accurately set at any of the different temperatures required for different crystals or to produce different wave lengths.

Having described my invention I claim:—

1. An instrument containing a capillary bore, 15 a bulb communicating with the bottom of said bore, a spillway above and communicating with said bore, a temperature sensitive liquid in said bulb and bore and a chamber containing an auxiliary pool of temperature sensitive liquid, means of a material not wetted by said liquid for constricting flow from said spillway into said bore, said pool being movable into said spillway and sealing the top of said bore in the upright position of the instrument, the maximum pressure head of the pool in the spillway being insufficient alone to force liquid downward past said constricting means.

2. An instrument comprising a tube containing 30 a capillary bore and a chamber communicating with the bottom of said bore, the upper end of said tube being bent to form a plurality of chambers, one of said chambers being positioned above said bore, a temperature sensitive liquid 35 in said bulb and bore, an electrically non-conducting rod having a section disposed in said bore and of a material not wetted by the temperature sensitive liquid, and an auxiliary pool of temperature sensitive liquid shiftable from one to the other of said chambers, the maximum pressure 40 head of the auxiliary pool shiftable into the chamber above the bore being insufficient to alone force liquid downwardly past said rod in any position of the instrument.

3. An instrument containing a bore and a substantially U shaped end forming chambers, one of which communicates with said bore, means comprising a glass rod constricting passage through the bore adjacent to said last named chamber, and a liquid pool movable from one to the other of said chambers, the maximum pressure head of the movable liquid pool shiftable into said chamber communicating with the bore being insufficient to alone force liquid downwardly past said rod into the bore in any position of the instrument.

4. An instrument comprising a glass tube containing a capillary bore and chambers communicating with each end of said bore, a glass rod 60 fixed to a wall of one of said chambers and having an end section depending into said bore, the upper end of said tube being bent to substantially U form, a temperature sensitive liquid of a character non-wetting toward glass in the chamber opposite said U end of said tube, and an auxiliary pool of temperature sensitive liquid in the U shaped end of said tube, the maximum pressure head of the auxiliary pool shiftable into the chamber containing the rod being insufficient 65 to alone force liquid downwardly past the rod.

5. An instrument comprising a tube containing a capillary bore, a bulb communicating with the bottom of said bore, a spillway above and communicating with the bore, the upper end of 75

said tube being bent to form a chamber communicating with said spillway above the bottom thereof, a temperature-sensitive liquid in said tube and adapted to form a main body in said bulb and bore and an auxiliary body in said chamber, and means of a material not wetted by said liquid for constricting communication

between said spillway and bore and permitting passage of liquid from said spillway to said bore only when said spillway is full of liquid and the meniscus of the main body of liquid is below said constricting means.
